UNITED STATES PATENT OFFICE.

CARL B. HUTCHINS, OF ALGONA, IOWA.

DISK-SHARPENER.

1,333,112.

Specification of Letters Patent.

Patented Mar. 9, 1920.

Application filed March 27, 1919. Serial No. 285,551.

To all whom it may concern:

Be it known that I, CARL B. HUTCHINS, a citizen of the United States, residing at Algona, in the county of Kossuth and State of Iowa, have invented certain new and useful Improvements in Disk-Sharpener; and I do declare the following to be a full, clear, and exact description of the invention, such as will enable others skilled in the art to 10 which it appertains to make and use the same.

This invention relates to improvements in disk sharpeners and has for its primary object the provision of a device for sharpening 15 the disks of plows without removing them from the scraper brackets or the gangs from the machine.

Another object is to provide a device of this character in which the grinding element 20 is adjustable according to the height of the disks from the ground.

A further object is to provide a device of this character including a novel means for supporting and rotating plow disks while 25 they are being sharpened.

With these and numerous other objects in view, the invention resides in certain novel features of construction and in unique combinations of parts to be hereinafter fully described and claimed, the descriptive matter being supplemented by the accompanying drawing wherein:

Figure 1 is a perspective view of the invention applied to use, and

35 Fig. 2 is a transverse sectional view illustrating the method of clamping the sharpening device to the lever.

In these drawings which constitute a part of the application, and in which similar 40 reference characters designate corresponding parts throughout the several views, the letter A indicates the cultivating disks mounted on a shaft B whose ends are rotatably mounted in bearings C formed on the 45 parallel arms extending from the scraper bracket D, all of well known construction.

For the purpose of supporting the disks in rotatable position, a pair of jacks or supports 1 are positioned beneath the bearings 50 on the arms of the bracket D, said jacks each comprising an elongated rectangular base block 2 adapted to support a vertically disposed block 3, said blocks being secured together by means of a pair of parallel 55 spaced bolts 4, whose threaded ends extend a considerable distance above the upper face

of the last named block 3. The vertical blocks 3 are disposed at the farthermost end of the base block from the source of power for rotating the disks, so as to form a brace 60 to prevent tipping over the entire device when motion is given the disks. To further assist in retaining the jacks in proper position stakes 6 are driven in the ground at the inner ends of the base blocks 2 as illustrated. The bearings C are adapted to be disposed between the extensions on the bolts to prevent relative movement of the jacks and bearings. 65

Although the disks may be rotated by 70 other practical means, I have provided a pulley 5 formed in two sections and preferably, though not necessarily made of wood. The two sections are secured together around the shaft by means of bolts as clearly 75 illustrated in Fig. 1 of the drawings. A belt of any suitable construction may be extended around said pulley and over the pulley of a motor, gas engine or the like so as to rotate the disks. 80

The sharpening device is mounted on a stake or lever 8 of a suitable length, said lever being provided on its lower end with a substantially triangular metal prong adapted to project into the ground to support the lever. The upper end of the lever is shaped to form an operating handle. The sharpening device 7 is preferably rectangular in shape and formed of carborundum or emery stone. The means for holding the 90 sharpening device on the lever includes elongated metal plates or arms 10 disposed on the edges of the lever and sharpener, one pair on each edge, said plates being provided with substantially centrally disposed 95 apertures which receive the bolts 9. The bolts are adapted to be disposed between the sharpening device and the lever and upon threading the nut on the bolt it is obvious that the plates 10 will be clamped tightly 100 against the lever and sharpener. Although I have described the clamping means as comprising two pairs of plates, it is obvious that two single plates of greater dimensions could well be used in place of the pairs of 105 plates. With the herein described clamps, the sharpening device may be adjusted vertically as required by the distance of the disks from the ground.

In operation the disks being rotated and 110 the sharpener properly adjusted the stone is brought into and out of contact with the

disks by lateral pressure on the operating lever 8. It is readily seen that the rapid rotation of the disks in contact with the sharpening device will quickly sharpen them and in view of the fact that it is unnecessary to remove the disks from the shaft a minimum length of time is used for the operation.

In the drawings, certain specific details of construction have been shown for accomplishing probably the best results, and in the preceding, such details have been described, but it is obvious that I need not be restricted thereto otherwise than claimed.

I claim—

15. A sharpening device of the class described comprising a lever substantially rectangular in cross-section, a flat substantially tri-

angular metal prong secured to one flat side of said lever and extending beyond the lower end thereof to project into the ground, 20 a substantially rectangular sharpening block disposed on one flat side of the lever, a pair of vertically spaced clamping plates on the adjacent vertical edges of the lever and block, said plates having bolt holes substantially midway their length, a pair of bolts disposed between the block and lever and extending through said bolt holes whereby the clamping plates may be tightened against the block and lever to secure the block in its 25 adjusted positions.

In testimony whereof I have hereunto set my hand.

CARL B. HUTCHINS.
